[57] **CLAIM**

The ornamental design for wall-mounted, multi-switch control unit for a programmable building system, as shown.

DESCRIPTION

FIG. 1 is a front and upper left perspective view of a wall-mounted, multi-switch, control unit for a programmable building system showing our new design;
FIG. 2 is a rear elevational view thereof;
FIG. 3 is a right side elevational view thereof;
FIG. 4 is a front elevational view thereof;
FIG. 5 is a left side elevational view thereof;
FIG. 6 is a top plan view thereof; and,
FIG. 7 is a bottom plan view thereof.
